UNITED STATES PATENT OFFICE.

CHARLES W. COOPER, OF NEW YORK, N. Y.

APPARATUS FOR EVAPORATING LIQUIDS.

SPECIFICATION forming part of Letters Patent No. 521,946, dated June 26, 1894.

Application filed January 12, 1894. Serial No. 496,625. (No model.)

To all whom it may concern:

Be it known that I, CHARLES W. COOPER, a citizen of the United States, residing in the city, county, and State of New York, have invented certain new and useful Improvements 5 in Apparatus for Evaporating Liquids, of which the following is a specification.

My invention relates to that class of evaporating apparatus which is organized to embody systems of evaporating tubes, and of which an apparatus invented by me and patented to me in and by United States Letters Patent No. 482,340, dated September 13, 1892, is a type, the said apparatus being one into 15 which the liquid may be continuously fed, from which it may be continuously discharged, and within which it may be caused to continuously circulate, while at the same time the supply may be controlled to an extent sufficient to secure a high rate of concentration.

Apparatus of the foregoing character is commercially employed for the evaporation of cane and beet sugar, condensed milk, glue, sugar of milk, soap lye, chrome liquor, and 25 all other liquors requiring economical distillation or evaporation.

The object of my invention is the construction in a simple and compact form of an evaporator embodying a plurality of separating compartments radially disposed with reference to a common central heating chamber and a common separating chamber, and communicating with each other in series.

An evaporating apparatus embodying my invention and into which the supply is continuous, out of which the discharge is continuous, and within which the circulation of the liquid is continuous, is represented in the accompanying drawings and hereinafter described, the particular subject-matter which I claim as novel being hereinafter definitely specified.

In the accompanying drawings, Figure 1 is a central, vertical, sectional elevation, through an apparatus embodying my improvements, the section being supposed in the plane of the dotted lines 1-1 of Fig. 2, —6—6 of Fig. 3, — and 7—7 of Fig. 4. Fig. 2 is a horizontal sectional plan through the apparatus of Fig. 1 in the plane of the dotted line 2—2 upon said Fig. 1, with the cover plate removed. Fig. 3 is a similar view of the said apparatus

in the plane of the dotted line 3—3 of Fig. 1. Fig. 4 is a similar view of the same apparatus in the plane of dotted line 4—4 of said Fig. 1; and Fig. 5 is a horizontal, sectional plan through the casing of the tube-supply compartments in the plane of the dotted line 5—5 of Fig. 1.

Similar letters of reference indicate corresponding parts.

In the drawings, A represents a central, vertically erected, heating chamber, preferably cylindric, and formed with an upper tube-head a and a lower tube head a' . Through these tube-heads the respective extremities of a series of groups of vertically-disposed, parallel, open-ended, evaporating tubes B, or equivalent passage ways or conduits, pass steam-tight. The heating chamber is supplied through a steam inlet a' with steam to circulate around and heat the exterior surfaces of the evaporating tubes. The chamber is also supplied with an outlet a^2 for the water of condensation.

C is a separating chamber the body of which is preferably cylindric, which is preferably formed with a hemi-spherical or conical dome having a vapor outlet c , and which, in the organization represented, is concentrically disposed with respect to the heating chamber in such manner as to encompass and inclose the upper portion of said chamber, from the outside surfaces of the walls of which the preferably downwardly and outwardly inclined floor c^2 of said separating chamber extends, and to which it is connected in any such preferable manner as may aid in the support of the chamber and preserve the relationship of the parts. The lower portion of the separating chamber is, as shown in Fig. 3, divided up into a series,—happening in the construction shown to be a series of six,—radial chambers or compartments which I term the separating compartments c^3 , and which are formed by a series of radial partitions c' extending from the outer walls of the heating chamber to the inner walls of the separating chamber, and from the floor of said separating chamber upwardly and in the construction shown to the plane of application of the dome-shaped upper portion of the separating chamber. The upper tube-head a of the heating chamber is, 95 as will be best understood by a reference to

75

100

Figs. 1 and 2, formed or otherwise provided with a series of vertical radial partitions c^3 ,—which, in connection with a cover plate A' supported at a suitable distance above the 5 upper tube head, and with an encompassing circular vertical flange a^3 , form a series of radial compartments which I term the tube-discharge compartments c^4 , and which,—by reason of the fact that the partitions c^3 are 10 in radial alignment above, and as to their lower edges are in actual contact, or, if desired, integral with, the radial partitions c' ,—are in connection with the corresponding compartments c^2 formed in the lower portion of the separating chamber, continuations of 15 which compartments, they, the said tube-discharge compartments, in fact, are.

From a reference to Figs. 1 and 2 it will be understood that, by reason of the fact that the cover plate A' and wall or flange a^3 are 20 of less exterior diameter than the interior diameter of the separating chamber, an annular opening c^5 common to all of the separating compartments c^2 is embodied within the 25 separating chamber and circumscribes the circular flange a^3 . This opening c^5 serves to permit the vapors escaping from out the tube-discharge compartments and deflected by the cover plate, to pass through the separating 30 compartments into which they are first discharged and thence into the upper portion or dome of the separating chamber for escape through the vapor outlet c . It is inconsequential how the partitions c' and c^3 be 35 formed and applied, and also immaterial by what means the cover plate and flange be applied and supported.

A convenient construction utilizing tubular sockets c^6 formed in the partitions and 40 bolts c^7 adapted thereto to retain the cover plate, is represented in the drawings.

Each of the separating compartments c^2 throughout the series, excepting of course the first and last compartments, is in communication with both compartments circumferentially adjacent to it, preferably through openings c^8 conveniently formed as horizontal slots through the radial partitions. Whatever be the number of compartments which 45 the apparatus as an entirety possesses, these 50 openings are placed upon different and successively lower levels,—the opening from out the compartment into which the liquid is first supplied into the next succeeding compartment, being higher than the opening from out said succeeding compartment into that 55 into which the liquid is next introduced, and so on throughout the series, and the opening from the next to the last compartment into 60 the compartment into which the liquid is finally introduced prior to its discharge from the apparatus, occupying the lowest level of any opening of the series, while the discharge opening from the final compartment is at a 65 still lower level. While, therefore, the form of the openings between the compartments is not of the essence, yet the levels upon

which the openings are, *seriatim*, disposed, and also the relationship of said openings with regard to their respective successive 70 levels above described, are important.

c^9 is a portion of a pipe, one or a series of which may be employed as outlets from the compartments of the separating chamber; which are, of course, provided with any preferred form of stop cock or valve; and which serve as escape outlets for water or other preferred liquid employed in the cleansing of the separating chamber of the apparatus. 75

D is the inlet for the liquid to be evaporated, 80 by which said liquid is conveniently introduced to the first compartment of the series.

D^x is the outlet through which the condensed liquid is withdrawn from the last compartment of the series. 85

E is a series of vertical tubes channels or conduits, which I term the return conduits, and which respectively lead outwardly and downwardly from the floors of the respective separating compartments, to, and so as to discharge into, a corresponding series of radially disposed tube-supply compartments e , formed within a preferably cylindrical tube-supply casing e^x formed and applied at the base of the heating chamber, beneath the lower tube 95 head a' , as shown in Figs. 1 and 5. The construction of this casing is not of the essence, but it may be conveniently that represented in the foregoing figures of the drawings. However the casing may be formed, each of 100 the compartments which it embodies is vertically aligned below a corresponding compartment in the upper portion of the apparatus, the partitions e' which divide the tube-supply compartments e , lying in the same vertical planes as the partitions c^3 which divide the tube-discharge compartments c^4 . 105

e^2 is a series of discharge orifices formed in the bottom plate of the tube-supply casing e^x one in each compartment, and conveniently controlled by a pivoted valve e^3 controlled by a hand lever e^4 , as shown in Fig. 1. These orifices serve to empty the evaporator of such liquid as remains when the operation is completed. 115

The construction and mode of application of the return conduits are, of course, immaterial. They may be conveniently applied in the manner shown in the drawings, but they may, if desired, be formed as a part of the 120 casting of the casing of the heating chamber. As will now be understood, especially by reference to Fig. 2, the same evaporating tubes which are in communication above with a given tube-discharge compartment of the separating chamber, are in communication below with the corresponding tube-supply compartment of the divisional tube-supply chamber considered as an entirety. In the apparatus represented six evaporating tubes open into 125 each of the respective corresponding tube-supply and tube-discharge compartments. Of course the number of tubes employed is 130 arbitrary in the same manner as is the num-

ber of compartments which the apparatus as an entirety is organized to embody.

Having now described an apparatus conveniently embodying my improvements, its 5 operation will have been sufficiently understood,—suffice it, therefore, to add, that, assuming a charge of liquid supplied to the first separating compartment of the series, the liquid therein will be caused to circulate down 10 the return conduit of said compartment into the corresponding tube-supply compartment, up the heating tubes which open into said compartment and into the tube-discharge compartment into which said tubes discharge,— 15 and that in the course of this continuous circulation the excess of liquid fed in over that evaporated will overflow into the next succeeding compartment of the series, and will circulate therein as in the first compartment, 20 the excess again overflowing into the next compartment, and the operation described being repeated throughout the series. No reverse flow is possible, and the apparatus as a 25 whole may be considered as one embodying a plurality of distinct evaporators,—each division forming a complete single continuously supplying and continuously discharging evaporator,—all of which, however, are operative with a common vapor and liquid separating 30 chamber.

Without further particularization of the apparatus and its mode of operation, it is sufficient to add that the operation proceeding within each of the conjoined compartments 35 of the series is the same as that described as taking place in each of the distinct compartments of the apparatus of my former patent referred to, and that the object of dividing the apparatus into compartments, broadly considered, is the same.

Having thus described my invention, I claim and desire to secure by Letters Patent—

1. An evaporating apparatus in which provision is made for the continuous supply, 45 continuous circulation, and continuous discharge, of liquid to be concentrated, and wherein are combined the following elements:—a central heating chamber embodying evaporating tubes;—a vapor and liquid separating chamber of diameter in excess of that of the heating chamber and encompassing 50 the upper portion of said heating chamber;—a series of radially disposed separating compartments formed in the lower portion of the separating chamber, circumscribing the heating chamber, and in communication respectively with given evaporating tubes, and, except as to the first and last, with each other;—a corresponding series of radially disposed tube-supply compartments located at the base of the heating chamber, corresponding with the separating chambers, and respectively communicating with corresponding given evaporating tubes;—and a series of return conduits corresponding in number 55 with the separating compartments and plac-

ing said compartments respectively in communication with corresponding tube-supply compartments;—substantially as set forth. 70

2. An evaporating apparatus in which provision is made for the continuous supply, continuous circulation, and continuous discharge, of liquid to be concentrated, and wherein are combined the following elements:—a central heating chamber embodying evaporating tubes;—a vapor and liquid separating chamber of diameter in excess of that of the heating chamber and encompassing the upper portion of said heating chamber;— 80 a series of radially disposed separating compartments formed in the lower portion of the separating chamber, circumscribing the heating chamber, in communication respectively with given evaporating tubes, and, except as to the first and last compartments, in communication with each other through the medium of openings through the partitions which separate the compartments, placed upon different and successively lower levels;—a corresponding series of radially-disposed tube-supply compartments located at the base of the heating chamber, corresponding with the separating chambers, and respectively communicating with corresponding given evaporating tubes;—and a series of return conduits corresponding in number with the separating compartments and placing said compartments respectively in communication with corresponding tube-supply compartments;—substantially as set forth. 95

3. An evaporating apparatus in which provision is made for the continuous supply, continuous circulation, and continuous discharge, of liquid to be concentrated, and wherein are combined the following elements:—a central heating chamber embodying evaporating tubes;—a vapor and liquid separating chamber of diameter in excess of that of the heating chamber and encompassing the upper portion of said heating chamber;—a series of radially-disposed tube-discharge compartments located above the heating chamber and in part circumscribing it, and inclosed laterally by a wall of less diameter than the separating chamber in order that an annular opening may be formed;—a corresponding series of radially-disposed separating compartments formed, as continuations of said tube-discharge compartments, in the lower portion of the separating chamber, circumscribing the heating chamber, and in communication respectively with given evaporating tubes, and, except as to the first and last, with each other;—a corresponding series of radially-disposed tube-supply compartments located at the base of the heating chamber, corresponding with the separating chambers, and respectively communicating with corresponding given evaporating tubes;—and a series of return conduits corresponding in number with the separating compartments and placing said compartments respectively in communication with corresponding tube- 125 130 135

supply compartments;—substantially as set forth.

4. An evaporating apparatus in which provision is made for the continuous supply, 5 continuous circulation, and continuous discharge, of liquid to be concentrated, and wherein are combined the following elements:—a central, vertically erected, heating chamber embodying a series of evaporating 10 tubes or passage ways for liquid which extends completely through it from end to end;—means for supplying a heating medium to the exterior of said evaporating tubes or passage ways;—a vapor and liquid separating chamber of diameter in excess of that of the heating chamber, concentrically disposed relatively thereto, and encompassing the upper portion of said heating chamber;—a series of 15 radially-disposed separating compartments 20 formed in the lower portion of the separating chamber, circumscribing the heating chamber, and in communication respectively with given

evaporating tubes, and, except as to the first and last, with each other;—a corresponding series of radially-disposed tube-supply compartments located at the base of the heating chamber, corresponding with the separating chambers, and respectively communicating with corresponding given evaporating tubes,—a series of return conduits corresponding in number with the separating compartments and placing said compartments respectively in communication with corresponding tube-supply compartments;—and liquid inlets and outlets applied respectively to the 30 first and last of the separating compartments;—substantially as set forth.

In testimony that I claim the foregoing as my invention I have hereunto signed my name this 3d day of January, 1894.

CHARLES W. COOPER.

In presence of—

J. BONSALL TAYLOR,
F. NORMAN DIXON.
